UNITED STATES PATENT OFFICE.

CHESTER A. FLANAGAN, OF UNION, OREGON.

DESIGN FOR A WALL-POCKET OR MUSIC-RACK.

No. 38,077.

Specification for Design.

Patented June 12, 1906.

Application filed April 30, 1906. Serial No. 314,584. Term of patent 14 years.

To all whom it may concern:

Be it known that I, CHESTER A. FLANAGAN, a citizen of the United States, residing at Union, in the county of Union and State of Oregon, have invented a new, original, and ornamental Design for Wall-Pockets or Music-Racks, of which the following is a specification, reference being had to the accompanying drawing, forming part thereof.

The figure is a perspective view of a wallsocket or music-rack, showing my new design.

I claim—

The ornamental design for a wall-pocket or music-rack, as shown.

CHESTER A. FLANAGAN.
